UNITED STATES PATENT OFFICE.

JOSEPH R. LAMB, OF JACKSONVILLE, ILLINOIS, ASSIGNOR TO AMBROSE MARRIOTT, OF ST. LOUIS, MISSOURI.

IMPROVEMENT IN BOILERS.

Specification forming part of Letters Patent No. **157,184**, dated November 24, 1874; application filed October 20, 1874.

To all whom it may concern:

Be it known that I, JOSEPH ROBERT LAMB, of Jacksonville, Morgan county, State of Illinois, have invented certain new and useful Improvements in Boilers for Water-Heaters, and other purposes, of which the following is a specification:

In this improvement the boiler is constructed of a number of parallel longitudinal vertical sections, each consisting of a top and bottom longitudinal pipe, slightly inclined from the horizontal, and the said pipes being connected by a number of vertical pipes of cruciform cross-section. The sections are connected together by transverse pipes at bottom and top, as shown.

Figure 1 is a perspective view of my apparatus, the front wall, one of the side walls, and the crown being removed. Fig. 2 is a longitudinal section at *x x*, Fig. 3. Fig. 3 is a horizontal section at *y y*, Fig. 2.

A is the wall or casing surrounding the boiler. This case may be of brick, metal, or other suitable material. *B* is the furnace-door, and *C* the chimney. *D D* are horizontal side pipes through which the feed-water enters. These pipes end at front in sockets *d*, for the ends of the water-supply (or return) pipes, whose ends are inserted in the sockets and secured by a rust-joint. The side pipes *D D* extend backward each side of the fire-grate and connect with the ends of the rear transverse pipe *E*, which has upon its upper side a number of sockets, *F F*, &c., each to receive the end of a vertical pipe, *G*, secured in said socket by a rust-joint. *H* is a pipe which forms a forward continuation of the pipe *G*, the pipe *H* inclining slightly upward as it extends forward. *I I*, &c., are vertical pipes extending upward from the pipe *H* and forming the water-communication between the pipe *H* and a pipe, *J*, parallel therewith, and extending from the back to the front of the case, where is an enlargement or socket, *j*, by which connection is made with a short pipe, *J'*, which is one of a number extending backwardly from the transverse pipe *K*. The joint *j*, like those aforesaid, is a rust-joint.

Thus, the boiler consists of a number of

vertical parallel sections, *G H I J*, connected together and having water communication through transverse pipes at bottom in the rear, and at top in front.

All the pipes except those, *I*, may be round, but the pipes *I* are cruciform in section, (as shown in Fig. 3,) having longitudinal extensions or hollow ribs *i*, and transverse extensions or hollow ribs *i'*.

The pipes *I* are so arranged that the transverse extensions or ribs *i'*, in one section, are opposite to the spaces *i* between the pipes in the contiguous sections, this arrangement allowing the heated currents to have free upward movement and to heat effectually the whole surface of the pipes *I*.

When using the boiler for water-heater, for heating buildings, for baths, &c., the water flows out through the pipe *K* to the radiators, and returns through the pipes *D D*.

When using as a steam-boiler, the pipe *K* may be made of sufficient diameter to constitute a steam-drum, or may communicate with a steam-drum over it; and also, the rear ends of the pipes *J* may communicate with the pipe *E* by vertical circulation pipes extending down through the body of the case *A*, or outside the case, so as to allow the water to have a downward flow through these pipes.

My preferred mode of manufacture is to cast the side pipes *D D* separate from the transverse pipe *E*, and to cast the necks or sockets *F* upon the latter. The neck or pipe *G*, pipes *H* and *I I*, &c., and pipe *J*, of each section, are cast in one piece. The joints between pipes, wherever joints are required, are rust-joints, as shown, the iron cement being tamped into the necks or sockets around the ends of the pipes.

I claim—

As an improvement in a boiler, the combination of sections formed of longitudinal pipes *H* and *J*, and vertical pipes *I*, cruciform in transverse section, and the transverse connecting-pipes, all substantially as set forth.

JOSEPH ROBERT LAMB.
